12 Claims. (Cl. 200—87)

This invention is concerned with electromagnetic relays comprising a magnet constructed of a flux member and a core member, an armature the free end of which extends between the pole pieces of the magnet, and a magnetizing winding which is associated with the poles of the magnet and common to the magnet and the armature.

In such relays, the magnet and the armature are disposed with respect to the magnetizing winding in such a manner that the armature is upon energization of the winding repulsed from the pole of the flux member which is in normal position of the armature nearest thereto while being attracted by the oppositely disposed pole of the core member.

In prior relay structures of this type, parts of the iron circuit are also utilized as electrical conductors. This is preferably effected by placing a circuit which is to be controlled on the armature and on the flux member, respectively, whereby the above indicated parts of the magnet are electrically mutually insulated, the armature being electrically separated from these parts.

In a known embodiment, a contact carried by the armature cooperates as a make contact with a contact carried by the core member which it engages in attracted position of the armature. It is moreover known to dispose upon the core member an individual contact bracket which carries the counter contact cooperating with the armature contact.

Known relays are also equipped with break contacts in addition to the above indicated make contacts. For example, there may be provided an additional contact point on the armature for engagement, in normal position of the armature, with a contact point disposed upon the flux member and thus forming a break contact therewith.

The above last described break contact structure exhibits several disadvantages. While the contact pressure is in the case of the make contact supplied by the attractive force of the magnet, the contact pressure for the break contact must be supplied by the force of the armature restoring spring. Since the armature must also carry the magnetic flux, its cross-sectional area must be considered in the dimensioning thereof so that it suffices for carrying the flux; that is, when using in known manner an armature constructed in the form of a resilient lamina, its resilience can be related to the contact requirements only insofar as the condition with respect to the carrying of the flux is satisfied.

It has been found in many cases that the contact pressure of such a break contact cannot satisfy the requirements in view of the magnetic properties of the armature which have to be met. Attempts have been made to overcome this difficulty by making the flux member of a permanent magnet material, utilizing the permanent flux for exerting a force on the armature in the normal or resting position thereof. This expedient entails considerably increased costs for the corresponding relay structure.

Another disadvantage of this known break contact structure resides in a strong rebounding tendency, consequently chattering, since the kinetic energy of the armature can decay only in a swinging motion in the course of which the contact after it has been closed can be opened again once or several times. It has been found that this rebounding phenomenon cannot be completely suppressed

2

even by making the flux member of permanent magnet material.

The object of the invention is to produce, in connection with a relay of the above indicated kind, a break contact which does not exhibit the described disadvantages. This object is realized by providing the relay with a contact spring which is in normal position of the relay in engagement with the structural part carrying the counter-contact for cooperation with the armature contact and causing this engagement to be interrupted by the armature in the attracted position thereof.

The structure according to the invention may be used in connection with relays of the indicated kind, in which the counter-contact for cooperation with the armature contact is directly provided on the core member, as well as in connection with relays which are in known manner provided with a contact bracket carried upon the core member, such contact bracket carrying the counter-contact for cooperation with the armature contact.

10 The previously mentioned disadvantages are avoided by the invention. The resilience characteristic of the contact spring may be determined independently of considerations regarding the flux flow and may thus be accurately provided in accordance with given requirements.

15 A further advantage of the structure and arrangement according to the invention is seen in the fact that twin-contact points may be employed which provide advantages as compared with single contact points, while twin-contact points provided on the armature would necessitate slotting which would adversely affect the flux flow in the armature and therewith the operation of the relay.

20 In accordance with a further object and feature of the invention, in relays having the individual parts thereof, such as flux member, core member, contact bracket and armature in known manner assembled in an insulating body, the contact spring can likewise be disposed in a slot of the corresponding insulating body by a simple plug-in operation.

25 Such an insulating body may be advantageously provided with projections for backing the contact spring. As will be presently explained more in detail, the use of such projections makes it in particularly advantageous manner possible to place the contact spring in position without requiring adjustment operations, especially when the same projections also serve for backing the core member.

30 The various objects and features of the invention will appear in the course of the description of an embodiment of a relay comprising a contact bracket and having its individual parts disposed in layers in an insulating body, which will be rendered below with reference to the accompanying drawing.

35 In the drawing,
FIG. 1 shows in perspective representation a relay;
FIG. 2 indicates parts in normal or resting position of the relay; and

40 FIG. 3 indicates the corresponding parts in attracted position of the relay armature.

45 The relay shown in FIG. 1 is equipped with a single iron circuit and its individual parts are disposed in layers in the insulating body 1. The insulating body 1 may be part of a relay bar comprising a plurality of relays. The core member 2 is L-shaped and has its long leg inserted in grooves formed in the guide chamber 3 of the insulating body. The flux member 4 is formed by a U-shaped structural part the two legs of which are inserted in grooves formed in the guide chambers 3 and 5, in such a manner, that the leg lying in the chamber 3 is positioned adjacent the longer leg of the core member 2, the free end of the second leg which extends from the chamber 5 overlapping outside of the chamber with the short leg of the core member. The overlapping forms the working air gap. The armature 6 is made in the form of a lamina

which lies upon the flux member in the chamber 5 so that its free end is disposed opposite the short leg of the core member. This armature lamina may be part of the U-shaped resilient sheet metal piece which is inserted into the chamber together with the core member or may be formed as a rigid lamina and provided with an L-shaped resilient metal strip serving for its positioning and restoration and correspondingly inserted into the insulating body together with the flux member. The energization or excitation winding 7 of the relay is pushed in position on the guide chamber. The flux member is provided with an insulating coating.

A contact bracket 8 which is placed upon the side of the core member 2 facing away from the armature, is inserted therewith in grooves formed in the guide chamber 3. This contact bracket is slotted and extends with its angular portions 9 and 10 into the space between the guide chamber and the edge of the short leg of the core member lying opposite thereto.

In accordance with the invention, there is provided a contact spring 13 which is inserted in grooves of the guide chamber 5 so as to form a backing for the contacts 11 and 12. The contact spring extends through the guide chamber, its soldering tab 14 projecting rearwardly therefrom as shown.

The contact spring is at its forward end provided with lateral extensions which rest against projections 15 and 16 at the frontal end of the guide chamber 5. FIG. 1 shows the projection so as to show the structure clearly.

As will be seen from FIGS. 2 and 3, the core member also rests against the identical contact surfaces of these extensions which serve for the backing of the contact spring. The contact spring therefore lies on the same plane as the core member; tolerances accordingly do not appear at all.

The operation of the break contact shall now be explained with reference to FIGS. 2 and 3 showing parts of the relay respectively in non-operated and in operated position. The various structural parts are referenced in accordance with FIG. 1.

In FIG. 2, showing the arrangement in non-operated position of the relay, the armature 6 lies flat on the flux member 4, the armature being provided with a cylindrical contact point 17. The contacts of the contact bracket 8 rest against the contact point of the contact spring 13. Accordingly, in this condition of the relay, a circuit is closed which extends by way of the contact bracket 8 and the contact spring 13.

As will be apparent from FIG. 3, when the armature 6 is attracted by the core member 2, the contact point 17 of the armature engages the contact point 12 of the contact bracket and lifts these contact points from engagement with the contact spring 13. The corresponding circuit is thus interrupted and another circuit is closed extending by way of the armature 6 and the contact bracket 8.

The above described break contact structure operates practically without rebounding. The mass of the armature 6 is greater than that of the contact bracket 8; accordingly, as will be seen from the drawing, the force of attraction of the armature is stored in the contact bracket and is upon deenergization utilized for the restoration of the armature. The stored contact force is greater than the force of the armature restoring spring. The armature, upon restoration, accordingly guides the contact bracket not abruptly but in damped manner toward the contact spring 13, the armature continuing its restoring motion to normal position without affecting the break contact. The kinetic energy remaining in the contact bracket does not produce rebounding or chattering of the break contact but, as has been found, is dissipated by swinging motion of the rearward end of the contact bracket 8 in damped manner about its normal position and in part in contact friction, without causing any contact opening.

It may also be mentioned that the contact points may be advantageously coated with noble metal.

The illustrated embodiment may of course be modified. As will be readily seen, the invention may also be applied in connection with relays of the described kind the individual parts of which are stacked in layers instead of being inserted into an insulating body. It is also understood that the invention is not limited for use in connection with the described and illustrated individual parts including the iron circuit and the contact bracket but may be employed in structures differing therefrom. For example, the flux member may be E-shaped, the core member and the contact bracket may be U-shaped and provided with correspondingly arranged contact extensions or projections. The contact spring may likewise assume different shapes. It is, for example, possible to employ a slotted contact spring so as to make the twin-contact points completely independent of one another. The backing for the contact spring is not absolutely necessary as such spring may extend freely from the guide chamber.

These and other changes and modifications are accordingly possible within the scope and spirit of the appended claims which define what is believed to be new and desired to have protected by Letters Patent.

I claim:

1. An electromagnetic relay comprising a magnet including a flux member and a core member, an armature extending with the free end thereof between the poles of said magnet, a magnetizing winding common to said magnet and said armature, said armature being utilized as an electrical conductor and closing in its attracted position an electrical circuit by engagement with contact means cooperating therewith, a structural member carrying said last named contact means normally positioned adjacent said core member, a contact spring which is in normal position of said armature in engagement with said structural member, movement of the latter, responsive to operative actuation of said armature, effecting disengagement of said structural member with said contact spring.

2. An electromagnetic relay according to claim 1, wherein the contact portion of said structural member is at the free end thereof slotted to provide twin contact points therat.

3. An electromagnetic relay comprising a magnet including a flux member and a core member, an armature extending with the free end thereof between the poles of said magnet, a magnetizing winding common to said magnet and said armature, said armature being utilized as an electrical conductor and closing in its attracted position an electrical circuit by engagement with contact means cooperating therewith, a structural member carrying said last named contact means, a contact spring which is in normal position of said armature in engagement with said structural member, said engagement being interrupted responsive to operative actuation of said armature, and an insulating body for supporting said magnetizing winding, the individual relay parts being inserted in layers in said insulating body, said contact spring being inserted into guide means formed in said insulating body.

4. An electromagnetic relay comprising a magnet including a flux member and a core member, an armature extending with the free end thereof between the poles of said magnet, a magnetizing winding common to said magnet and said armature, said armature being utilized as an electrical conductor and closing in its attracted position an electrical circuit by engagement with contact means cooperating therewith, a structural member carrying said last named contact means, a contact spring which is in normal position of said armature in engagement with said structural member, said engagement being interrupted responsive to operative actuation of said armature, a contact bracket cooperating with said core

member, said bracket carrying said contact means cooperating with said armature, said contact spring being in normal position of said relay in engagement with said contact means, and a contact member carried by said armature which is operative upon attraction of said armature to lift said contact means carried by said contact bracket from engagement with said contact spring.

5. An electromagnetic relay according to claim 4, comprising an insulating body for supporting said magnetizing winding, the individual relay parts being inserted in layers in said insulating body, said contact spring being inserted into guide means formed in said insulating body.

6. An electromagnetic relay according to claim 3, wherein said contact spring is widened to form lateral extensions at the forward contact-making end thereof.

7. An electromagnetic relay according to claim 5, wherein said contact spring is widened to form lateral extensions at the forward contact-making end thereof.

8. An electromagnetic relay according to claim 6, 20 wherein said insulating body forms projections for backing the lateral extensions of said contact spring.

9. An electromagnetic relay according to claim 7,

wherein said insulating body forms projections for backing the lateral extensions of said contact spring.

10. An electromagnetic relay according to claim 8, wherein said projections are also operative as backings for said core member.

11. An electromagnetic relay according to claim 9, wherein said projections are also operative as backings for said core member.

12. An electromagnetic relay according to claim 4, 15 wherein the contact portion of said contact bracket is provided at an extension which projects in the direction of the contact portion of said contact spring, said portion being slotted at the free end thereof to provide twin contact points thereat, said slotting extending into said contact bracket.
